GEAR SHIFTING CONSOLE FOR A BICYCLE

Viktor Schreckengost, Cleveland Heights, Ohio, assignor
to The Murray Ohio Manufacturing Co., Nashville,
Tenn., a corporation of Ohio

Filed Mar. 1, 1967, Ser. No. 6,018

Term of patent 14 years

(Cl. D90—1)

FIGURE 1 is a top plan view of a gear shifting console for a bicycle showing my new design;

FIGURE 2 is a side elevational view thereof;

FIGURE 3 is a front elevational view thereof;

FIGURE 4 is a rear elevational view thereof; and

FIGURE 5 is an elevational view taken from the side opposite that shown in FIGURE 2.

I claim:

The ornamental design for a gear shifting console for a bicycle, substantially as shown.
